UNITED STATES PATENT OFFICE.

FRANCIS W. KRAMER, OF PHILADELPHIA, PENNSYLVANIA.

TOY RAILWAY.

1,096,632.

Specification of Letters Patent. Patented May 12, 1914.

Application filed January 12, 1914. Serial No. 811,504.

To all whom it may concern:

Be it known that I, FRANCIS W. KRAMER, a citizen of the United States, residing in the city and county of Philadelphia, State 5 of Pennsylvania, have invented a new and useful Toy Railway, of which the following is a specification.

My invention consists of a railroad more particularly designed as a toy, the same 10 composing a body adapted to simulate a road bed, and raised portions thereon at intervals adapted to simulate railroad ties, said portions being provided with cheek pieces to clamp miniature railroad rails to 15 said portions, the whole forming a simple, inexpensive and comparatively unbreakable play thing for the purpose intended.

The invention is satisfactorily illustrated in the accompanying drawing, but the important instrumentalities thereof may be varied, and so it is to be understood that the invention is not limited to the specific 20 details shown and described.

Figure 1 represents a top or plan view 25 of a toy railway embodying my invention. Fig. 2 represents a transverse section on line $x-x$ Fig. 1. Fig. 3 represents a longitudinal section of a portion on line $y-y$ Fig. 1.

Similar numerals of reference indicate 30 corresponding parts in the figures.

Referring to the drawings:—1 designates a base which is made to simulate the road bed of a railway, and is formed preferably 35 of sheet metal, arch-shaped in cross section for the purpose of strength. The plate is swaged and struck-up at intervals forming transversely-extending parallel ridges 2, which rise above what may be termed the 40 crown of the arch shaped road bed and are flat at the top thereby simulating the cross ties of a railroad and are adapted to support the railroad rails 3 placed thereon. On said ridges are the lips 4 which are punched

upwardly out of the material of said ridges 45 and comprise chairs or cheek pieces which embrace opposite sides of the bases of the rails and clamp them to the ridges or ties 2, and preventing under ordinary circumstances, the displacement of the rails. 50

It will be seen that the device is strong, inexpensive, durable and comparatively non-breakable toy, one that may be used by children for running miniature cars on the rails thereof, and provides an enjoyable 55 plaything for the purpose intended.

Having thus described my invention what I claim as new and desire to secure by Letters Patent, is:—

1. A toy railway comprising in a single 60 integral element a longitudinal base member arch-shaped in cross section and simulating a railway road bed, transverse ridges at intervals on the crown of said base member simulating cross ties, and rail clamps 65 on said ridges.

2. A toy railway comprising in a single integral element a longitudinal base member arch-shaped in cross section and simulating a railway road bed, transverse ridges 70 at intervals on the crown of said base member simulating cross ties, and rail clamps on said ridges, said ridges being raised above said crown.

3. A toy railway comprising in a single 75 integral element a longitudinal base member arch-shaped in cross section and simulating a railway road bed, transverse ridges at intervals on the crown of said base member simulating cross ties, and rail clamps on 80 said ridges, said ridges being of less length than the width of the base member and being raised above said crown.

FRANCIS W. KRAMER.
